ACCOUNT-REGISTER.

938,214.

Specification of Letters Patent. Patented Oct. 26, 1909.

Application filed September 23, 1908. Serial No. 454,390.

To all whom it may concern:

Be it known that we, CARL CLUNDT and JOHN REIDT, both citizens of the United States, residing in the city and county of San Francisco and State of California, have invented new and useful Improvements in Account-Registers, of which the following is a specification.

Our invention relates to a system for keeping account of credit sales of merchandise.

In grocery stores and elsewhere it is usual to make out sales slips in duplicate or triplicate, giving the purchaser one of the slips, and the other going to the bookkeeping department where the proper entries in the books are usually made. Where a credit business is carried on, the customer is supposed to keep his slips, and the bill when rendered him by the store will tally with the total of these slips. Frequent misunderstandings and disputes arise between the storekeeper and customer by reason of the latter losing or misplacing one or more of his duplicate slips; and various other inconveniences arise by the usual system of keeping accounts.

The object of our invention is to provide a system whereby the chances of error or misunderstanding arising will be reduced to a minimum; and in which is employed, suitable envelopes or holders for keeping not only a summary of the individual accounts, but which envelop or holders will contain a facsimile of the account slip handed the customer.

The invention consists of the parts and the construction and combination of parts as hereinafter more fully described and claimed, having reference to the accompanying drawings, in which—

Figure 1 is a perspective, partly broken away, of an envelop embodying our invention. Fig. 2 is a vertical section of the envelop.

The envelops 2 constitute the principal feature of the present invention. They may be of any suitable size, shape and material. Usually they are made of stiff paper and are open at the top with a projecting tab member 8 in continuation with the back of the envelop, and on which tab portion 8 may be written the name of the customer corresponding with this envelop. The front of the envelop is provided with suitable means for removably holding a record or account sheet, as 9, as desired, also an under-

neath carbon 10 and an underneath duplicating record sheet 11. As here shown, the means for removably holding these register slips 9 comprise a pocket 12 at top and bottom of the front of the envelop, the mouths of the pockets being opened toward each other, and each having an inturned clamping lip or strip 13 underneath which and against the front of the envelop an end of the record strip is easily slipped, but which clamp 13 serves to hold the slip or slips from being easily detached or pulled loose from the envelop. Usually these pockets are formed by folding a strip of stiff paper 70 which is either in continuation of the top and the bottom of the front of the envelop, or may be pasted thereto, this strip of paper being folded twice on itself, so that the portion 13 projects into the pocket and coats 75 as a clamp, in the manner described, with the body of the envelop; a strip of suitable fabric 14 being pasted across the folded strip which carries the clamp 13, and closing the sides of the pocket and being carried 80 around and the ends pasted on the back of the envelop. The record strips or slips 9—11 may be of special design, or they may simply be slips from an ordinary manifolding salesbook.

In practice, this account register is used in the following manner: At the beginning of the month, or whenever a credit account is opened, one of these envelops is taken, the customer's name written on the tab 90 portion 8, and a record sheet 9, and if desired, a duplicate sheet or slip 11 and carbon 10 are engaged in the pockets 12. When a sale is made to this customer he is given the original tag, and the duplicate tag is placed 95 in the customer's envelop after the salesman has made his entry on his record sheet 9 showing the date of the sale, the number of the tag put in the envelop, and the total of the sale. The next day, or any other 100 time when a sale is made to this same customer, the operation is repeated; the customer getting his original tag, the salesman making his proper entry on his record sheet 9 and then placing the duplicate tag in the 105 customer's envelop. From the tags in the envelop the bookkeeper makes up his books. The record sheet 9 thus becomes an itemized bill and is rendered to the customer at the proper time, the duplicate sheet 11, however, 110 being placed in the customer's envelop or otherwise preserved. In this way all the

tags of each customer are carefully kept together, and no chances for a dispute or misunderstanding over the loss of a tag by the customer may arise, and any discrepancy or error is easily corrected.

In order to facilitate the insertion and the removal into the envelop of the limp tags, we may employ a folded strip 15 of stiffish material which acts as a supplemental holder 10 to be inserted into the envelop with the ends of this holder 15 projecting slightly above the mouth of the envelop so as readily to be grasped by the fingers.

Having thus described our invention, what 15 we claim and desire to secure by Letters Patent is—

1. In an account register, an envelop having a main pocket adapted to receive record slips, and having supplemental top and bottom pockets on its front surface adapted to form holders for an account slip removed from the main pocket, said supplemental pockets having means for engaging the account slip with a clamping action.
2. In an account register, a tag holder comprising an envelop member open at one end, the ends of the front of the envelop being returned parallel with said front to

form outside pockets adapted to receive a record tag, said pockets having their entrances presented toward each other and the extremities of said ends being turned inwardly to engage the inserted record tag.

3. In an accounting system, the combination of an envelop, and means for removably holding a record sheet thereon, said last-named means comprising opposed pockets opening toward each other, with spring clamping members inside the pockets.

4. In an accounting system, the combination of an envelop open at one end and having the back portion of the envelop projecting beyond the front of the envelop, said envelop having opposed pockets on its outside opening toward each other, and a folded holder insertible into the envelop substantially as described.

In testimony whereof we have hereunto set our hands in presence of two subscribing witnesses.

CARL CLUNDT.
JOHN REIDT.
